Patented July 28, 1914.

UNITED STATES PATENT OFFICE.

CHARLES D. WILSON, OF TOLEDO, OHIO.

WRENCH.

1,105,475.

Specification of Letters Patent.

Patented July 28, 1914.

Application filed February 13, 1914. Serial No. 818,573.

To all whom it may concern:

Be it known that I, CHARLES D. WILSON, a citizen of the United States, residing at Toledo, in the county of Lucas and State 5 of Ohio, have invented certain new and useful Improvements in Wrenches; and I do hereby declare the following to be a full, clear, and exact description of the invention, such as will enable others skilled in the art 10 to which it appertains to make and use the same.

This invention relates to wrenches and has for an object to provide a combination of quick acting and screw adjusting wrench.

15 A further object of the invention is to provide improved means for actuating the movable jaw and with improved means for reducing the friction of such jaw in its movement.

20 With these and other objects in view the invention comprises certain novel constructions, combinations and arrangement of parts as will be hereinafter more fully described and claimed.

25 In the drawings: Figure 1 is a view of one embodiment of the wrench in side elevation. Fig. 2 is a view of the wrench in edge elevation. Fig. 3 is a view of the wrench with the rigid jaw in side elevation and the movable jaw in section. Fig. 4 is a transverse 30 sectional view of the wrench taken on line 4-4 of Fig. 3.

Like characters of reference designate corresponding parts throughout the several 35 views.

The improved wrench which forms the subject matter of this application comprises a rigid jaw member 10 integral with the handle member 11 in substantially the usual 40 and ordinary manner and provided with the customary rack 12 extending along one edge. Upon the handle and over the rack 12 a movable jaw 13 is mounted controlled by a knurled worm 14 engaging the rack 12. 45 The knurled worm 14 is journaled upon the movable jaw 13 in any usual and ordinary manner as by the employment of a pintle 15 having a reduced neck 16 and held in position by a pin 17. The knurled worm

and its manner of mounting is, however, 50 not peculiar to the present invention and forms no part thereof.

The opening through which the handle member 11 extends is made wider than ordinary and at the side opposite the knurled 55 worm 14 provides a considerable space as indicated at 18. The space thus provided permits a limited angular movement of the pivoted jaw 13 about the points 19 and 20 to the extent that the knurled worm 14 may 60 be moved out of engagement with the rack 12 and permit the sliding jaw to move freely without the restraint of such engagement. To hold the knurled worm 14 normally in engagement with the rack an index pin 21 65 is provided having a head within the chamber 18 slidable upon the handle member 11 rounded to reduce friction. A spring 22 surrounds the pin 21 and is seated in a socket 23 formed in the wall of the chamber 18 70 so that such spring 22 and the head of the pin 21 may be seated largely if not entirely within such socket. It is obvious, therefore, that when manual pressure is exerted upon the rear end of the movable jaw member the 75 jaw will be moved against the tension of the spring 22 to clear the knurled worm 14 from engagement with the rack 12 so that said jaw member may be freely moved along the handle. To provide for such manual en- 80 gagement and movement of the jaw a knurled shoulder 24 is provided at such en- gaging point.

To facilitate the movement of the jaw along the handle member a socket 25 is pro- 85 duced in the forward end of the movable jaw 13 adjacent the point 19 as shown more particularly at Fig. 3. Within this socket 25 a spring 26 is inserted and a ball 27 mounted upon the end of the spring in en- 90 gagement with the handle member upon the side opposite the pin 21. The particular ob- ject of this ball and spring arrangement is to add ease to the movement of the jaw along the handle member more particularly 95 when the movable jaw has been moved so that the point 19 is in engagement with the rack 12. The ball 27 in such case prevents

the corner or point 19 from engaging in such rack and preventing the movement of the jaw.

I claim:

- 5 In a wrench, a rigid jaw and handle member having a rack along one side; a movable jaw slideable upon the handle member; means carried by the movable jaw for adjustably engaging the rack; a resilient member holding the adjusting member yieldingly in en-

gagement with the rack; a ball carried by the movable jaw; and a spring arranged to hold the ball in yielding engagement with the rack side of the handle member.

In testimony whereof I affix my signature in presence of two witnesses.

CHARLES D. WILSON.

Witnesses:

EARL O. BALES,
BENJ. V. L. BOYER.
